(57) **CLAIM**

The ornamental design for a mobile computing terminal, as shown and described.

DESCRIPTION

FIG. 1 is a top perspective view of a mobile computing terminal showing the new design;

FIG. 2 is a bottom perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines shown in the drawings represent portions of the mobile computing terminal which form no part of the claimed design.
